UNITED STATES PATENT OFFICE

2,425,749

BOLT LOCK FOR MACHINE GUNS

John L. Lochhead, Springfield, Mass., assignor
to the United States of America, as represented
by the Secretary of War

Application October 30, 1942, Serial No. 463,880

4 Claims. (Cl. 89—188)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to improvements in bolt locks for machine guns, such as disclosed in the United States Patent No. 1,628,226 to John M. Browning.

In a Browning gun provision for quick replacement of the barrel has made it expedient to finish the barrel with a planiform breech face extending flush to the chamber, and to secure the barrel in the barrel extension with the breech face extending into the barrel extension slightly. The chamber is of less length than the cartridge, so that the head of the cartridge projects while held in the T-slot of the bolt. Adjustment of the "headspace" between the barrel and bolt is a critical factor in operation of these guns and properly the bolt at battery does not press hard against the head of the cartridge, but is stopped by the tips of the T-slot engaging the barrel, and the breech lock is depended on to fix the bolt at its forward limit in the barrel extension. Consequently in the prior gun the advance of bolt relative to the barrel extension can not equal the extent indicated in Figure 8 but may be greater in other guns; or, the barrel extension of the Browning or other guns, using my invention may be constructed without any solid part to engage before and stop the bolt near or at battery position, but enabling my lock to effect such stoppage at a time when no shock will occur.

At times a machine gun of the type disclosed in the above-mentioned patent will fire out of battery due to the barrel extension going into battery ahead of the bolt. When such a condition occurs, it is impossible for the breech lock to be effective and the bolt and barrel extension will be dangerously unlocked at firing. A suitable breech locking mechanism to insure positive relative positioning and locking together of the recoiling parts approaching battery is therefore desired.

While under certain high rate of fire adjustments in the known use of the prior gun, firing is effected while the barrel extension is advanced slightly ahead of the bolt (advantage being taken of continuing momentum of the bolt to bring it into or near battery while explosion of the propellant is initiated) without immediate gun damage or misfiring. This is undesirable because recoil then sometimes occurs before the bolt is locked to the barrel extension, with severe shock or excessive wear or breakage, modification of

2

kinetic operating values of the recoiling and counterrecoiling parts, liability of cartridge case rupture, and otherwise. My invention obviates these liabilities of injury while permitting proper pre-battery firing.

Instructions for using the Browning gun stress the need for frequent adjustment of the headspace, every time the gun is cleaned or after every engagement. Insufficient headspace causes the bolt to jam against the prior Browning bolt lock, preventing full entry of such lock into the notch. This stops movement of the barrel extension to full battery position accompanied by sluggish action at least or may only prevent extraction of a new cartridge from the ammunition belt, or in an extreme case may stop the recoiling parts far enough rearward to prevent firing. Too much headspace has other manifestations of faulty operation accompanied by liabilities, including that of rupture of the cartridge case.

While my invention will not obviate the need for careful maintenance of proper headspace its use will minimize impaired function and stoppage resulting from lack of correct headspace.

Accordingly it is an object of this invention to produce an improved machine gun action.

Another object of this invention is to provide a breech lock for positive timing and locking of the recoiling members of a machine gun.

The specific nature of the invention as well as other objects and advantages thereof will clearly appear from a description of a preferred embodiment as shown in the accompanying drawings in which:

Fig. 1 is a partial side elevational view of a machine gun, partly broken away to show the bolt and barrel extension in battery.

Fig. 2 is a top elevational view of Fig. 1 with the cover partially broken away to show the belt feed lever.

Fig. 3 is a view partly in section showing the bolt and breech lock in an unlocked position.

Fig. 4 is a view similar to Fig. 3 but with the bolt and breech lock in battery position.

Fig. 5 is a cross-sectional view on line 5—5 of Figure 4.

Fig. 6 is an enlarged end view of the breech lock.

Fig. 7 is an enlarged front elevational view of the breech lock.

Figure 8 is a view similar to Figure 4, showing an earlier position of the parts when the bolt is too far advanced.

In Fig. 1 there is shown a partial longitudinal sectional view of a machine gun such as disclosed

in U. S. Patent No. 1,628,226 to John M. Browning which embodies this invention. The gun as shown in Fig. 1 comprises mainly a receiver 1, a trunnion block 2 and a cover 3. Slidably mounted within the receiver 1 is a bolt 7, a barrel 13 and a barrel extension 14. A belt feed lever 15 is pivotally mounted on the cover 3. The belt feed lever 15 is a long flat member having a narrow cam track 16, here shown as a slot (Fig. 2) in the center thereof which operates to impart a transverse movement to the lever 15 and hence to a belt feed slide or carrier 23 which is slidably mounted in the cover 3. The cam track 16 is defined by two oppositely disposed sides 17 and 18 of the belt feed lever 15 which conform generally in shape to the cam track 16. One end of the belt feed lever 15 projects forwardly to form a rounded end 19. The end 19 fits between two integral upwardly projecting lugs 24 and 25 provided on the belt feed slide 23. On the other end 20 of the belt feed lever 15 in the left side an outwardly projecting lug 21 is provided. A hole 22 is centrally provided in the projection 21 to mount the lever on the cover 3 by a bolt 26. The bolt 26 is inserted through either suitable hole 5 or 6 in the cover 3 and the bolt is secured to the cover 3 by a nut 27. A cotter pin 28 inserted in a suitable hole in the nut 27 and the bolt 26 prevents the nut 27 from unscrewing.

The cover 3 is pivotally mounted on the top of trunnion block 2 by a pin 4. When cover 3 is closed cam track 16 engages a stud 29 on bolt 7 so that belt feed lever 15 will be actuated by the reciprocating bolt to feed ammunition into the gun. The stud 29 is suitably secured in the center of an integral upwardly projecting lug 8 provided on the forward upper surface of the bolt 7. To aid in reducing friction between the cam track of the belt feed lever 15 and stud 29 a roller 30 may be suitably mounted on stud 29.

A rotary type of breech lock 31 is inserted in a suitable hole 38 in the barrel extension 14 approximately in the same location as the breech lock of conventional form. The lock 31 (Figs. 1, 6 and 7) is a cylindrical member having on each end similar coaxial longitudinally projecting portions 32 semi-annular and of the same radius vertically as the body of the lock. The lower edges 33 of the portions 32 are finished in a diametrical plane of the lock member, which thus affords two flat wiper or bearing surfaces 33 on the underside of each projection 32. A medial recess 34a is formed in the forward side of the lock, so that a planiform radial upper locking surface 34 is provided on the lock 31 extending from the axis of the lock to its periphery normal to the plane of the faces 33. A lower surface 34' slopes obliquely downward and forwardly at locked position of the lock, somewhat as shown in Fig. 6 and on the lower part of this surface 34' there is provided a small projecting lug 37 to limit rotation of the lock 31 in unlocking movement. A shallow transverse cut across the top of the lock 31 forms a wide U-shaped flat bottomed notch 35 of less width than the recess 34a. Two projecting horn-shaped members 36 are thus provided on each side of the notch 35. These may be termed horns. They assist the bolt into battery position as will be presently described. A notch 9 is provided on the underside of the bolt 7 to provide part of a locking surface 10 for the lock 31. The notch 35 in the lock 31 allows a lock part 48 under the notch 35 to be rotated into the notch 9 in the bolt 7 so that the locking sur-

face 34 of the lock 31 engages the locking surface 10 of the bolt 7.

On each side of the bolt 7 a recess 11 corresponding approximately in form to the horns 36 but of a greater radius, so as to normally clear the horns above and behind, as in Figures 4 and 5 is provided to permit the horns 36 to engage in these recesses and to assist the bolt into battery as will be explained. The forward sides of these recesses form continuations of the surface 10 of the recess 9, these continuations extending to a sufficient height to receive the forward planiform sides of the horns 36 thereagainst. A breech lock cam 39 is fixed on the bottom of the receiver, arranged to guide the barrel extension and to actuate the breech lock 31. This cam is of somewhat different configuration than the conventional breech lock cam because of the entirely different construction of the rotary lock 31. The breech lock cam 39 is a U-shaped member (Fig. 5) arranged transversely of the receiver having upwardly projecting arms 40 and 41 close beside respective sides of the receiver, and on the interior surfaces of the arms there are formed respective inwardly projecting ribs 42. The ribs 42 engage suitable grooves provided in the barrel extension 14 to support and guide the barrel extension within the breech lock cam 39 as the barrel extension 14 reciprocates therein. The upper rear corners 43 (Fig. 1) of the upwardly projecting arms 40 and 41 of the breech lock cam 39 are suitably rounded to provide a camming surface to engage one lower face 33 of each lock extension 32 when the barrel extension is returning to battery and impart a rotary motion to the lock 31 to lock the counterrecoiling bolt and barrel extension or the like of a machine gun as they move to battery position. The upper surfaces 44 (Fig. 1) of the arms 40 and 41 provide a suitable engaging surface for the bearing surfaces 33 when the lock is in the locked position. The cam 39 is secured to the bottom plate of the receiver by the bolt 46.

The cycle of operation of the machine gun shown in Fig. 1 is similar to that disclosed in the previously mentioned patent to John M. Browning. The bolt 7 reciprocates in a straight line within the receiver after the discharge of each cartridge and effects feeding and loading of rounds by recoil and counterrecoil as well as ejecting shells as desired. Conventional trigger firing and recoil devices, operating substantially as in the prior gun mentioned, may be used.

In Fig. 1 and Fig. 4 recoiling parts of the gun are shown in the locked or battery position; that is, they are in position to permit safe firing of a cartridge. When the lock is in this position the surfaces 33 on the lock 31 rest on the surfaces 44 of the cam 39 and the locking surface 34 of the lock 31 engages the locking surface 10 in the locking notch 9 provided on the underside of the bolt 7. Also, the part 48 below the recess 35 engages in and fills the notch 9 to the rearward side of the latter, and the bolt may therefore be said to be locked to the barrel extension. As shown in its preferred form, the locking surface 34 of the lock 31 and the locking surface 10 of the bolt 7 are formed at right angles to the lock surface 44 of the cam 39 so that they will engage each other in a plane normal to the paths of the bolt and barrel extension. Such a locking surface affords a locking function of high effectiveness and utmost strength with a minimum of material and liability of looseness by wear, strain or plastic deformation. In addition,

when the bolt 7 is in the forward position shown in Figs. 1 and 4 the horns 36 provided on the lock 31 engage the forward sides of the recesses 11 provided on the bolt 7.

When a cartridge is fired the force of the explosion forces the recoiling members, namely, the bolt, barrel extension and barrel to slide towards the rear, such members being held in locked relation by lock 31 recoiling as a unit therewith. When the rear faces 33 of the lock 31 reach the rounded corners 43 of the cam 39, as the recoiling members are driven rearwardly, the lock 31 tends to rotate around corner 43. Unlocking rotation of the lock is induced by pressure of the bolt face 10 against lock face 34. The pressure of the bolt in this way is developed by the greater impedance offered to the recoil of the barrel extension by the conventional buffer springs, aided usually by a dash pot device. As the rearward movement of the recoiling members continues complete unlocking is effected by further rotation of the lock by bolt 7. This is accomplished by the pressure exerted by the bolt at 10 on the locking surface 34 of the lock 31 well above the axis of the lock 31 thereby creating considerable leverage which facilitates rotation of the lock. It will be noted that the face 34 extends high on the horns 36, and a wiping action of the bolt continues thereon (at the angle formed by the junction of the bottom face of the bolt and the lower part of the surface 10) after the part 43 has moved clear of the recess 9. After unlocking, the bolt, assisted as in the prior art by an accelerator 45 (which converts some of the energy of recoil of the barrel extension to acceleration of the bolt), travels rearwardly to the end of its stroke. During the latter part of this assisted movement of the bolt in the Browning guns, as is known, the accelerator is moved by the barrel extension to a locking relation with the barrel extension by which the latter is held at full recoil position until return of the bolt over a major part of its travel in counterrecoil.

In the unlocked position as dotted in Figure 3 the wiping or bearing surfaces 33 and the bottom of recess 35 assume a vertical position and the projection 37 contacts the bottom of the bolt 7 thereby preventing further rearward rotation of the lock 31. The recoil movement of the barrel and barrel extension is of comparatively short travel but is sufficient to permit lock 31 to be rotated sufficiently to fully unlock and assume the position shown in Fig. 3.

The bolt 7 is returned to battery position by an operating spring (not shown). As the bolt approaches the position at which it is to be locked to the barrel extension, accelerator 45 is engaged by a projecting portion 12 of the bolt 7 which moves the accelerator so as to release the barrel extension for return by its recoil spring (not shown) and further aided by the bias of a spring (not shown) acting on the accelerator. This permits and also initially assists the barrel extension and barrel to go forward about the time the bolt is locked by the lock 31. As is the common function of the prior bolt with the accelerator, and is also manifest with my invention, the relation between the bolt and accelerator is normally such that the bolt can not, at the time it strikes the accelerator move ahead of the barrel extension, because the accelerator forms an operating connection for the moment which fixes their relative position except when the accelerator is excessively worn, and under the latter condition the bolt may be slightly in

advance of its proper position for locking to the barrel extension. After the accelerator has been completely operated and is in its forward position the parts normally move forwardly in a predetermined relation suitable for the function of my lock as above indicated and hereinafter explained. As the barrel and barrel extension proceed forward the rear edges of cam 39 contact the lower surfaces 33 of lock 31 and rotate lock 31 forwardly. Such rotation causes horns 36 to project upwardly and into recesses 11 on bolt 7. The bolt 7 meanwhile is continuing its forward motion. Upon engagement of the horns 36 in recesses 11 the cam 39 completes rotation of the lock and the counterrecoiling members continue forward while rigidly joined by the lock into battery position, the lock 32 having been rotated into its fully locked position as shown in Fig. 4. The locking surface 34 of lock 31 then fully engages locking surface 10 of bolt 7 and the bearing surfaces 33 of each extension 32 both lie fully engaged on the top of cam 39. Further rotational movement of the lock is thus prevented.

If, for any reason, the bolt tends to move ahead of the barrel extension at or immediately after the function of the accelerators, the extremities of the horns 36 will nevertheless have been raised in the lower parts of the recesses 11 as in Figure 8, before the bottom of recess 35 reaches the level of the lower face of the bolt, and they will engage the rear sides of the recesses 11, if the relative movement extends so far, well before the part 43 of the lock strikes the bottom of the bolt, stopping any excess in rate of bolt counterrecoil over movement of the barrel extension. Thereafter, the conventional oil buffer spring or corresponding recoil means for the barrel extension, being the more powerful, will accelerate the barrel extension and prevent any further relative advance of the bolt in relation to the barrel extension. My lock may then function normally as before described. While the extreme condition of Figure 9 will not occur in the current Browning gun lesser errors of position of the bolt will be similarly remedied before the lock part 43 strikes the bolt. Construction of the Browning gun so that the T-slot lips are not depended on to stop advance of the bolt in the barrel extension will eliminate breakage of the lips now occurring from this cause.

In the functioning of the bolt and barrel extension after operation of the accelerators, any tendency for the bolt to become essentially retarded will be overcome by the function of the horns 36 against the angle at the lower parts of the face 10 of the recess 11 so that the bolt is pressed forwardly by the horns until the locking part 43 may enter the recess 9 snugly and the face 34 abuts the lower part of the locking surface 10, as shown in Figure 4. Completion of the movement of the parts to battery is thus coordinated. This will prevent excessive headspace and attendant evils in many cases which have heretofore occurred in the Browning gun.

It may thus be readily seen that with this type of lock it is impossible for the bolt and barrel extension to go into battery in any position but the fully locked mutual position because of the projecting horns 36 which engage in the recesses 11 on the bolt regardless of how late or soon the bolt is returned to the accelerator on the closing stroke.

I claim:

75 1. In a machine gun having a receiver and a

recoiling barrel, a barrel extension and a bolt reciprocable on the barrel extension; a locking assembly comprising a cylindrical lock body rotatably supported transversely in the barrel extension, a longitudinal projection on each end of said body having wiper parts located at opposite sides of the axis of the lock body, a fixed cam engaging said wiper parts and operative under movement of the barrel extension to engage the wiper parts and rotate said cylindrical body, a central transverse notch being formed in said bolt and a recess formed in the side of the bolt extended from the notch rearwardly and above the notch, the forward walls of said notch and recess being coincident and shaped to form a locking surface, an extension on said body to extend above said notch to engage in said recess, the rear wall of said recess arranged to engage said extension as the bolt approaches battery position, whereby the engagement of said extension with said recess wall will prevent the bolt going ahead of the keyed position of the bolt relative to the barrel extension, said cylindrical body having a lock part to engage and fill said notch and being rotatable by engagement of said cam against said wiper parts to engage said locking surfaces of the bolt and lock body and engagement of said lock part in said notch at the normal locked positions of the bolt and barrel extension.

2. In a machine gun having a receiver, a recoiling barrel and barrel extension having a battery position therein, and a bolt slideable in and from the extension reciprocable in the receiver over a longer path than that of the extension and having a predetermined battery position, means to lock the bolt and said extension in a mutual firing relation during their counterrecoil in advance of and at said battery position, comprising a transverse U-shaped cam fixed in the receiver for reciprocation of the barrel extension therein, a generally cylindrical lock revolvably mounted in the barrel extension with its axis transverse to the cam, said lock having a medial recess to receive the bolt slidingly therethrough at one position of the lock, said bolt having a lock notch therein having front and rear faces arranged to align with the rear part of the lock when the bolt is in said firing relation to the barrel extension, said lock having a rearward locking part to fit the said faces of said notch when the lock is 50 rotated forwardly at said firing relation of the said extension and bolt, said lock having an axial extension having two wiper faces in a common plane on opposite sides of the axis of the lock, said cam having an arm beside the barrel extension stopping near and below the axis of the lock and having a rear cam face positioned rearwardly of the battery position of the lock axis, said cam having also a horizontal upper face positioned to engage slidingly under both said wiper faces of 60

5 the lock over a limited extent of travel of the barrel extension, the distance of the rearward wiper from the center of said lock being sufficient for it to engage the rear cam face when the lock is in open position in counterrecoil, whereby to be rotated to move on to said upper face, and to move the other wiper face commonly to and slidably on said upper face.

10 3. The structure of claim 2 in which the rear cam face is vertical, a rounded face on the cam forming a junction of said cam faces, said wiper faces being in a common plane coincident with said upper face of the cam at locked position of the lock, said wiper faces being spaced apart more than the length of the chord of said rounded part of the cam.

15 4. The structure of claim 2, in which the said notch and locking part have top faces intermediately of the height of a vertical radius of the lock, said lock having a horn shaped part extended upwardly beside the bolt above the said locking part and said bolt having a safety recess in its side opening on the bottom of the bolt to receive said horn shaped part and extending above the notch, the rear part of the safety recess being rearward of the notch curved forwardly from its lowermost part to its forward side, the safety recess and said notch having their forward sides formed by a single planiform vertical face, intersecting the bottom of the bolt, said lock part and horn shaped part also having a single continuous face to engage flat against the other planiform face at locked position of the parts.

20 25 30 35 JOHN L. LOCHHEAD.
